UNITED STATES PATENT OFFICE.

ROY T. AXE, OF SYRACUSE, NEW YORK, ASSIGNOR TO THE O. M. EDWARDS COMPANY INC., OF SYRACUSE, NEW YORK, A CORPORATION OF NEW YORK.

WEATHER STRIP OR BUFFER FOR WINDOW SASHES.

Application filed September 11, 1925. Serial No. 55,764.

This invention relates to window sashes and has for its object a buffer or weather strip for engaging the window sill and readily conforming to all unevennesses in the sill and to sills of different inclinations.

The invention consists in the novel features and in the combinations and constructions hereinafter set forth and claimed.

In describing this invention, reference is had to the accompanying drawing which is a transverse sectional view through the lower rail of a window sash, the rail being shown in perspective.

This weather strip comprises a body attachable to the lower edge of the lower rail of the window face and having downwardly and inwardly extending lips which meet or which tend to meet along the apex or medium line of the strips when the strip is compressed by the sash against the sill.

1 designates the lower rail of a window sash and as here shown it is formed up of sheet metal and is open at its lower edge and provided with inturned flanges 2 at its lower edge.

3 designates the weather strip or buffer, which is here shown as attached to the lower rail by interlocking therewith and having lengthwise grooves 4 at opposite sides thereof of which interlock with the inturned flanges 2 upon endwise sliding movement of the weather strip. The body of the strip below the edge of the rail is preferably semi-cylindrical, that is, it is semi-discoidal in cross section and the two inwardly extending lips 6 are provided by forming the strip with a lengthwise tubular passage 7 and a slot or a slit 8 extending radially of the semi-cylindrical portion of the strip and opening through the apex line of the strip and into the passage.

When the sash is brought down onto the sill designated 10, these two inturned lips will compress toward each other and conform to unevennesses and also to the inclination of the sill and will form a weather proof joint between the sash and the sill.

The flanges 2 support the buffer or weather strip and receive the thrust thereof

and are located on opposite sides of the apex line of the buffer or the line where the buffer engages the sill. Owing to the relative location of the supporting means for the buffer and the line of engagement of the buffer and the sill, the lips 6 compress toward each other when the buffer compresses.

What I claim is:

1. A window sash comprising a lower rail, a weather strip for the lower rail comprising a body portion formed with downwardly and inwardly extending marginal lips, the lips being arranged to move toward each other at their edges during compression of the strip.

2. A weather strip for the lower rails of window sashes comprising a body extending lengthwise of the edge of the lower rail, the body being semi-cylindrical and arranged with its flat base toward the edge of the rail, the body being formed with a lengthwise passage opening through the apex of the semi-cylindrical surface of the body forming the body with inwardly compressible lips.

3. A weather strip for the lower rails of window sashes comprising a semi-cylindrical body arranged with its base toward the edge of the sash, the body being formed with a lengthwise tubular passage and with a radial slit opening from said passage through the apex of the semi-cylindrical surface.

4. A window sash comprising a lower rail, a weather strip for the lower rail comprising a body portion formed with downwardly and inwardly extending lips, the lips being arranged to move toward each other at their edges during compression of the strip, the body being formed with lengthwise grooves on opposite sides thereof and the lower rail of the sash being formed with flanges interlocked with the grooves.

In testimony whereof, I have hereunto signed my name, at Syracuse, in the county of Onondaga, and State of New York, this 3rd day of September, 1925.

ROY T. AXE.
